DESIGN.

C. BOOZE.
WALL PAPER.

No. 20,229.

Patented Oct. 21, 1890.

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,229, dated October 21, 1890.

Application filed September 27, 1890. Serial No. 366,394. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of leaves and flowers of the canna or Indian shot plant arranged in a continuous wave-like line running vertically up the paper, as represented in the accompanying photograph.

15 The leaves project from the vine in various directions over the surface of the paper and expose the flowers of the plant in full bloom between the leaves.

The design is printed in any desired color upon tinted paper of any desired color. 20

What I claim is—

The design for wall-paper herein shown and described.

Witness my hand this 13th day of September, 1890.

CHARLES BOOZE.
